(57) **CLAIM**

The ornamental design for a plant production container, as shown and described.

DESCRIPTION

FIG. 1 is left side view of a plant production container showing our new design;

FIG. 2 is a top, front perspective view thereof;

FIG. 3 is a bottom, front perspective view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top plan view thereof; and,

FIG. 9 is a bottom plan view thereof.

The broken lines showing an environmental plant in FIG. 1 and portions of the plant production container in FIGS. 1, 4, and 5 form no part of the claimed design.
